UNITED STATES PATENT OFFICE.

ALBERT GLENN LUKENBILL, OF PUEBLO, COLORADO, ASSIGNOR OF ONE-HALF TO CHARLES J. LEFTWICH, OF PUEBLO, COLORADO.

CANVAS CAMPING DEVICE.

No. 928,391.

Specification of Letters Patent.

Patented July 20, 1908.

Application filed April 6, 1908. Serial No. 425,423.

To all whom it may concern:

Be it known that I, ALBERT GLENN LUKENBILL, a citizen of the United States, and a resident of Pueblo, county of Pueblo, and State of Colorado, have invented a new and useful Improvement in Canvas Camping Devices, of which the following is a specification.

My invention relates to improvements in canvas camping devices in which the device is so constructed that it is applicable to divers uses; and the objects of my improvement are; first, to provide in one connected canvas device a tent that may be used in various forms, among them an A tent with carpet, a sunshade, a wall tent, a hospital tent, a sleeping bag, a hammock and a stretcher; second, to provide facilities for adjusting the device for the different uses, all in one construction; third, to provide a device for the uses stated that may be readily adjusted in small space for transportation and so arranged in construction and form, together with snaps and rings, that in connection with telescopic poles all parts are attached to avoid loss and to facilitate use. I attain these objects by the mechanism illustrated in the accompanying drawings in which—

Figure 1 is a plan view of my canvas device as it appears spread out flat with the several snaps, rings and flaps in place; Fig. 3 is a perspective view of my invention used as a sleeping bag; Fig. 2 is a perspective view of my invention applied as a wall tent; Fig. 4 is a perspective view of my invention applied as an A tent; Fig. 5 is a perspective view of my invention applied as a hospital A tent or sunshade; Fig. 6 is a perspective view of my invention applied as a hospital wall tent or sunshade.

Similar numerals refer to similar parts throughout the several views.

My canvas device in the form I have designed for attaining the several uses as set forth is found in Fig. 1 and consists of a rectangular parallelogram of canvas cloth included within the lines A, A, C, C, and may be constructed all as one part or with seams at lines B, the portion included within the lines A, A and B, B will constitute the roof of the tent, in which, at the apex, reinforcing rings 16 are placed for upright end poles; gable pieces 1, being four in number, are in the form of a right angled triangle, the hy-

potenuse of which is on line A, A, the apex or more acute angle at 16, the less acute angle at 12, attached to and made a part of the roof piece heretofore described, leaving space 3 as shown; the flap along line 3^a is 60 one-half the width of the tent; the portion to form the side walls is included within the lines C, A, A and B at each end of the structure; the end portions of the walls 2, 2, 2, 2, are made by extending the wall pieces or by 65 attaching to the wall pieces end pieces 2, 2, 2, 2, which are of the same height as the wall pieces and in length one-half of the width of the tent; attached to said gable pieces are weather flaps or strips 1^a and 3^a; attached to one of said wall pieces is flap 27; along lines B, B are loops 10, 10 and on one end reinforcing loops 9, 9; attaching to the canvas, rings 12; midway between reinforcing rings 16 and loops 9 laterally across the roof canvas are loops 10 with reinforcing loops 7 attaching to the canvas rings 5 and 11; attached to the bottom of each wall piece are loops 10 and rings, several in number, 8 and 14; snaps 15 are attached by similar loops on 75 the lower edge of wall piece opposite flap 27; on the gable piece of each end, loops and rings 6 attached to canvas correspond to and register with loops and snaps 6^a; loops and rings 18 on gable piece correspond to and 80 register with loops and snaps 18^a on adjacent end pieces 2; on the wall end pieces, 2, of each end, loops and rings 17 correspond to and register with loops and snaps 17^a; rings 6, 17 and 18 as well as snaps 6^a, 17^a, and 18^a 85 are on the opposite side of the canvas from all other rings and snaps and in any of the uses herein set forth will be on the inside.

To employ the device as a wall tent a telescopic ridge pole is extended by pulling 95 pipes 23 outwardly from including pipe 22, and securing them by set screw 24; end poles are extended by drawing pipe 20 out of including pipe 19, fastened by set screw 19^a, and in like manner drawing out pipe 21 100 from including pipe 20 and securing it by set screw 20^a; then end pins 21^a of each end pole are inserted in holes 23^a of the ridge pole and placed in rings 16 and poles are raised in place; ropes 4 are attached in rings 12 and fastened to guy stakes in the ground in ordinary manner; the walls of the tent then hanging perpendicularly may be staked to the ground through rings 14; end wall pieces 2 are brought to center of tent and by 105 1

fastening snaps 18^a in rings 18 the gable and wall end pieces are united and by fastening snaps 6^a in rings 6 the gable pieces of each end are fastened together; the end wall pieces 5 may be attached securely to the ground by stakes driven through rings 8; thus forming a wall tent as shown in Fig. 2. It may be seen that by detaching the snaps holding the gable pieces together at the ends, the gable 10 pieces 1 may be thrown back on or fastened under the roof of the tent, leaving the tent with complete walls around making a very desirable tent for use in warm countries or, when ventilation is desired, or for use in 15 countries infested by reptiles; or with the gables turned back as last indicated the device is readily adaptable for the use of stockmen on the ranges in retaining and protecting in stormy seasons the newly born stock; 20 the snaps and rings being unfastened, the end wall pieces may be detached and thrown back when it is desired to use the whole tent as a sunshade; or additional upright poles may be used, each of the end wall pieces 25 wrapped around the top of a corner pole and one-half of the tent raised and extended as a sunshade or for hospital purposes as shown in Fig. 6.

To use my contrivance for the purpose of 30 an A tent the end poles are adjusted to the required height and together with ridge pole placed in position, the walls of the tent are folded inwardly, end pieces 2 folding over or under wall pieces, thus avoiding 35 bunching, the flap 27 overlapping the corresponding wall piece at the middle of the floor, and the tent is fastened to the ground by means of ordinary stakes through rings 12, gable pieces to be fastened as was done 40 in wall tent, making a perfect A tent with canvas floor as shown in Fig. 4. To construct from the A tent formation a sunshade or hospital tent, by the use of additional corner poles one side of the roof is extended 45 with the wall forming a side shade as shown in Fig. 5.

To fold the canvas device for transportation as well as for use as a hammock, sleeping bag or stretcher, the device is spread out 50 with the rings 5, 8, 10, 11, 12 and 14, and snaps 15, underneath; the gable pieces 1 are folded back along lines A A on the roof piece; the wall piece on which is flap 27 is folded back over on the gable and roof pieces at line 55 B, the width of the wall piece, and then folded over so that line B lies on the other line B, or, over to the near edge of the opposite wall piece the remaining portion of the roof piece is then folded over the last previous 60 fold of wall piece; one of the end wall pieces 2 is then turned over the folds the opposite or other wall and end pieces are then brought over the top of the folds so far made, the remaining single end wall piece is folded under the folds; the snaps 15 are fastened to

rings 5, 5 and 11, 11 as in Fig. 3, thus leaving exposed at each corner reinforced rings 5 and 12. At this point the device is ready for 76 rolling for transportation or for the uses as a hammock sleeping bag or stretcher.

If it is desired to use the device as a sleeping bag, it being folded, the two wall end pieces 2 may be fastened together, the top one may be lifted and the person may get into the bag from the top placing any number of the folds he desires above him, and the bag has the advantage of a protecting top to prevent the storm from gaining entrance to the bag because the fastenings are at the side, and while in this position the two end 75 pieces may be fastened together with snaps 17^a and rings 17 and the same held above the sleeper's head by means of a pole held by cross stakes or some such means, as shown in Fig. 3.

The device being folded as explained, if it is desired for use as a hammock, ropes in corner rings 5 and 12 may be attached to trees or any suitable objects and the device swung 90 as a hammock; and if it is desired the device has the further advantage that when in the hammock formation the user may get in between the folds as when used for sleeping bag.

If it is desired to use the device as a 95 stretcher, being folded, tent poles, guns or other poles may be fastened by means of ropes 4 in rings 5, 11 and 12.

The whole device may be rolled and tied for transportation including therein telescopic poles and ropes and by this means the roll for transportation, with the addition of tent stakes, contains a complete contrivance 100 adaptable to the various uses herein set forth; and it is further seen from the construction of my device that the use shown in Fig. 5 and Fig. 6 may represent just one-half of a construction obtainable by the use of another device with the opposite side fastened down and the whole united in the middle by use of snaps 15 in one device being attached to rings 14 in an adjoining device.

Having thus described my device so that one versed in the art could construct and use the same, and knowing that canvases have 115 been made adaptable to similar uses what I claim is:—

1. In a canvas camping device composed of a sheet of fabric in the form of a rectangular parallelogram, four end wall pieces, four 120 triangular gable pieces, said end wall pieces and gable pieces being separate from each other, each end wall piece and each triangular gable piece attached to said parallelogram, engaging and registering snaps and 125 rings at the ends of said end wall pieces, substantially as described.

2. In a canvas camping device composed of a sheet of fabric in the form of a rectangular parallelogram, four end wall pieces, four 130

triangular gable pieces, said end wall pieces and gable pieces being separate from each other, each end wall piece and each triangular gable piece attached to said parallelogram, engaging and registering snaps and rings at the ends of said end wall pieces, engaging and registering snaps and rings on the lower edge of each triangular gable piece and upper edge of each end wall piece, engaging and registering snaps and rings on longer free edges of gable pieces, ring means on lower edge of gable pieces and at upper edge of side wall line on parallelogram to receive stakes when used as an **A** tent, said rings on upper edge of side wall line for guy fastenings when used as a wall tent, ring means at lower edge of end wall pieces and free edge of parallelogram to secure bottom edge to ground, substantially as described.

3. In a canvas camping device composed of a sheet of fabric in the form of a rectangular parallelogram, four end wall pieces, four triangular gable pieces, said end wall pieces and gable pieces being separate from each other, each end wall piece and each triangular gable piece attached to said parallelogram,

gram, each triangular piece fastened along its hypotenuse to the parallelogram with the more acute angle at the center of the long side of the parallelogram, engaging and registering rings and snaps around the free edge of the parallelogram, engaging and registering rings and snaps for the several end wall and gable pieces, rings 5 and rings 12 at loops 9 reinforced and intermediate rings 30 placed laterally on the parallelogram and snaps on free edge of parallelogram registering with said rings when device is folded as a sleeping bag, rings 5 and rings 12 at loops 9 when device is folded form means of attachment of device as a hammock and these with intermediate rings form means of attachment of device as a stretcher, substantially as described.

In testimony whereof I have signed my name to this specification in the presence of two subscribing witnesses.

ALBERT GLENN LUKENBILL.
